UNITED STATES PATENT OFFICE.

TIMOTHY P. CRONIN, OF ST. LOUIS, MISSOURI.

SPARK-PLUG.

1,302,319.

Specification of Letters Patent. Patented Apr. 29, 1919.

Application filed March 18, 1918. Serial No. 223,225.

To all whom it may concern:

Be it known that I, TIMOTHY P. CRONIN, a citizen of the United States of America, a resident of the city of St. Louis, in the State of Missouri, have invented certain new and useful Improvements in Spark-Plugs, of which the following is a full, clear, and exact description, reference being had to the accompanying drawings, forming a part of this specification.

This invention relates to improvements in spark plugs, and more particularly to means whereby the current is transformed and the spark intensified by the use of a number of electrodes arranged in series, with spark gaps between them, one of the spark gaps being formed at the lower end of the plug in the usual manner.

More specifically stated, an auxiliary spark gap is formed near the top of the spark plug so as to transform the current and produce a hotter spark at the main gap near the bottom of the plug. To obtain the most satisfactory results, the auxiliary spark gap must be formed near the main gap, for the increased voltage due to the transformation at the auxiliary gap would otherwise be reduced or dissipated before the current is transmitted to the main spark gap.

Hundreds of the specific devices herein shown and claimed have been placed in actual service on internal combustion engines, and, compared with ordinary spark plugs, the results have been a decided saving of fuel, elimination of the trouble usually due to the presence of carbon or oil on the spark plugs, and, owing to the increased efficiency of the spark, the engine can be started very easily.

The main electrodes in the engine cylinder are not short circuited or otherwise injuriously affected by carbon or oil, and the results have clearly shown that a comparatively lean explosive mixture can be used in a cylinder equipped with the new device. In other words, the sparks derived from the new device thoroughly ignite a lean mixture, and owing to the intensity of the sparks, the combustion is so perfect that the usual engine troubles due to imperfect combustion have been almost entirely eliminated. Consequently, more power is developed by an

automobile engine equipped with the new devices and the fuel consumption is greatly reduced.

These statements are based upon results obtained in actual practice and not upon the theory herein advanced, for I am aware that some of the statements founded upon theoretical considerations may be more or less inaccurate.

These important results have been accomplished by the use of an air-tight chamber near the upper end of the spark plug and a series of electrodes, two of which terminate in said air-tight chamber to form an auxiliary spark gap therein. The air-tight chamber is formed in a particular manner, as will be hereinafter described, so as to obtain the desired results at a low cost. The highest efficiency has been obtained by forming a point at the terminal of the transmitting electrode in the air-tight chamber and forming a relatively large head at the adjacent end of the receiving electrode. Actual service has shown that this produces most desirable results, and according to my understanding of the theory of operation, the small transmitting electrode opposing a relatively large face on the receiving electrode eliminates resistance, and the current is carried with greater force to the main gap in the engine cylinder.

When the new device is first placed in service, the sparks at the main gap are red and somewhat inefficient, but they soon become blue and very hot. The change is evidently due to the fact that the auxiliary gap is formed in a sealed air-tight chamber, and at the beginning some of the constituents of the air therein are consumed by the auxiliary sparks. Thereafter, the auxiliary sparks are not materially affected by the presence of air in the sealed chamber, and very hot blue sparks are then produced at the main gap.

The invention comprises the specific details involved in the production of the simple air-tight chamber, the peculiar relative proportions and construction of the electrodes therein, and other details of construction whereby a most efficient commercial article is produced at a low cost.

plug made in accordance with my invention, also showing a portion of the engine cylinder to which the plug is applied.

Fig. II is a horizontal section on line

5 II-II, Fig. I.

Fig. III is a side elevation, partly in section, illustrating a modification.

The device shown in Figs. I and II comprises a tubular metallic member 1 adapted 10 to be screwed into the wall 2 of an internal combustion engine. A central insulator 3 is secured to the member 1 by means of a bushing 4 screwed into the upper end of the member 1. A dome 5 is secured to the upper end 15 of the insulator 3 to form an air-tight chamber at the top of the plug. The dome 5 has an inturned bead 6 which lies in a recess at the upper portion of the insulator. The metal dome and insulator are thus interlocked with each other and they are preferably cemented together by means of a cement that will harden when subjected to a high temperature. In assembling the parts 20 the metal dome is preferably heated and thereby expanded, and then permitted to contract onto the upper portion of the insulator, the cement being interposed between the insulator and the heated dome.

The metal at the center of the dome is 30 preferably punched inwardly and threaded to receive a screw 7. A jam nut 8 on the screw 7 is seated against the top of the dome 5, and a binding nut 9 is fitted to the screw 7 above the nut 8. 10 designates the terminal of a conductor leading to the spark plug, said terminal being clamped between the nuts 8 and 9.

An intermediate electrode 11, located at 40 the center of the insulator 3, extends from the air-tight chamber at the upper end of the plug to a point near an electrode 12, extending from the tubular member 1, at the lower end of the plug. The intermediate electrode is separated from the end electrode 45 12 to form the main spark gap. An auxiliary spark gap is formed between the lower end of the screw 7 and the upper end of the intermediate electrode 11. The electrodes 7, 11 and 12 are so arranged that the spark 50 gaps are in series with each other. The lower end of the screw 7 is pointed and a relatively large head 13 is formed at the upper end of the electrode 11. The current passing from the screw, or electrode, 7 is 55 transmitted from the pointed lower end to the large face at the top of the head 13. By forming the ends of the electrodes 7 and 11 in this manner, resistance is eliminated and the current is carried with greater force 60 to the main gap at the lower end of the plug.

To obtain the best results the screw 7 can be adjusted toward and away from the head

13 so as to vary the width of the auxiliary spark gap, and the upper end of said screw is therefore notched to receive an adjusting tool.

In Fig. III I have shown a modification in the form of an attachment for an ordinary spark plug. The plug itself may be provided with the usual electrode 12' at its 70 lower end, and an electrode 11' extending from an insulator 3'. The electrodes 11' and 12' are separated from each other to form the main spark gap. 15 designates the usual binding nut screwed onto the upper 75 end of the electrode 11'. The attachment shown in Fig. III comprises an insulator 16, a dome 5' secured thereto to form an air-tight chamber, a screw 7' extending into the air-tight chamber, nuts 8' and 9' fitted to 80 the screw 7', an electrode 11^a arranged in the insulator 16 and provided with a head 13' opposing the pointed lower end of the screw 7', and a conductor 11^b connecting the electrode 11^a to the electrode 11' at the 85 center of the spark plug. The conductor 11^b is detachably secured to the spark plug by means of the binding nut 15. 10' designates a conductor clamped between the nuts 8' and 9'. It will be observed that the air-tight 90 chamber of the modification and the electrodes therein are constructed like the corresponding elements of Fig. I. However, instead of an intermediate electrode made of a single piece of material, the modification 95 includes the conductors 11^a, 11^b and 11', connected together to transmit current from the auxiliary spark gap to the main spark gap.

I claim:

A spark plug provided with an insulator, a metal dome cemented to the upper end of said insulator to provide a sealed air-tight chamber, an upper electrode comprising a screw threaded into said dome and extending 10: into said air-tight chamber, a lower electrode near the lower end of said insulator, an intermediate electrode arranged in said insulator and extending from said air-tight chamber to the lower end of the insulator, 11: said intermediate electrode being separated from said upper and lower electrodes to form a main spark gap at the lower end of the plug and an auxiliary spark gap in said air-tight chamber, the inner end of the 11: threaded upper electrode being pointed and the intermediate electrode being provided with an enlarged head opposing said pointed end, and a binding nut fitted to said threaded upper electrode.

In testimony that I claim the foregoing I hereunto affix my signature.

T. P. CRONIN.
